COMBINED LAMP AND COIN BANK

Edward L. Dickerson, 1402 Hales Drive,
Gustine, Calif.

Filed Nov. 27, 1964, Ser. No. 82,812

Term of patent 3½ years

(Cl. D48—20)

FIG. 1.

FIG. 2.

FIG. 3.

FIG. 4.

FIG. 5.

FIG. 1 is a top plan view of a combination lamp and coin bank, showing my new design.

FIG. 2 is a front elevational view, the back being the same as the front except for the addition of the bulb and reflector shown in FIG. 1.

FIG. 3 is a side elevational view.

FIG. 4 is a bottom plan view.

FIG. 5 is a perspective view thereof.

The cross hatching visible in FIGS. 2 and 5 designates the colors in the spectrum normally observed in a primary rainbow, with the exception of indigo, which has been indicated by combining a horizontal cross hatching for the color blue and the vertical dashed line used for the color violet.

I claim:

The ornamental design for a combined lamp and coin bank, as shown and described.
